UNITED STATES PATENT OFFICE.

WILLARD W. BARDSLEY, OF PROVIDENCE, RHODE ISLAND.

MECHANISM FOR INDICATING TIMELY ACTION IN LOOMS.

No. 907,451.

Specification of Letters Patent.

Patented Dec. 22, 1908.

Application filed February 26, 1906. Serial No. 303,039.

To all whom it may concern:

Be it known that I, WILLARD W. BARDSLEY, a citizen of the United States, residing at Providence, in the State of Rhode Island, have invented a new and useful Improvement 5 in Mechanisms for Indicating Timely Action in Looms, of which the following is a specification.

This invention relates to a mechanism which serves to indicate the proper time for 10 the performance of a specific movement in some portion of the mechanism of a loom, as for instance, the time for operating the shuttle-box motion. And it consists in the combination of a plurality of rotary annular 15 multiplying elements of different diametrical dimensions provided with means for positive engagement with a driver, and with peripheral means, which when arranged in proper line with one another serve to cause 20 the movement of an arm which is in indicative connection with the loom mechanism wherein a timely operative action is required.

In the accompanying drawings, Figure 1 represents a plan view of an indicating mechanism embodying my improvement. Fig. 2 represents a side elevation of the same. Fig. 3 represents an end elevation. Fig. 4 represents the opposite end elevation. Fig. 5 represents an enlarged section taken in the line 5 5 of Fig. 2. Fig. 6 represents an outer end view of the operating gear for the multiplying elements, and an outer side view of the connected stop wheel and ratchet wheel. Fig. 7 represents a side view of the operating gear, and an edge view of the stop wheel and the ratchet wheel. Fig. 8 represents a side view of one of the multiplying elements provided with a single peripheral notch. Fig. 9 represents an 10 edge view of the same. Fig. 10 represents a side view of one of the multiplying elements provided with a plurality of peripheral notches. Fig. 11 represents a vertical section taken in the line 11 11 of Fig. 2. Fig. 12 represents a vertical section taken in the line 12 12 of Fig. 45 2. Fig. 13 represents an enlarged side view showing a modification in which the multiplying elements are formed of unequal endless flexible chains. Fig. 14 represents a side 50 view of the upper portion of one of the said endless flexible chains. Fig. 15 represents an edge view of the same. Fig. 16 represents the side view of the sprocket wheels for the said chains, and the outer side view of the 55 connected ratchet wheel, the stop wheel be-

ing removed. Fig. 17 represents an edge view of the sprocket wheels and of the stop wheel and ratchet wheel. Fig. 18 represents a plan view showing a modification in which the indicating elements are located upon separate shafts instead of being placed side by side. Fig. 19 represents a side elevation of the same. Fig. 20 represents a side view of the opposite indicating arms of the mechanism. Fig. 21 represents the top view of an indicating arm adapted for employment in connection with rotary indicating elements provided with peripheral elevations, instead of the depressions. Fig. 22 represents a section taken in the line 22 22 of Fig. 21, showing the indicating arm in its raised position. Fig. 23 represents the same section showing the indicating arm in its lowest position. Fig. 24 represents a side view of one of the rotary multiplying elements having a single peripheral projection, the said multiplying element being shown on a diminished scale. Fig. 25 represents a side view of a multiplying element provided with three peripheral projections. Fig. 26 represents an edge view of the same.

In the drawing, A represents the frame of the machine, and B a fixed horizontal spindle which is held from rotation by means of the set screws *a a*. Upon the outer end of the 85 rock-shaft C is secured the reciprocating arm D, from which suitable connection is to be made with the motive power. And to the opposite end of the said rock-shaft C is secured the upright arm E, to the upper end of which are pivoted the gravitating ratchet pawls F and G, the pawl F operating upon the teeth of the ratchet wheel H, and the pawl G upon the teeth of the ratchet wheel I. The fixed spindle J is secured to the upper 90 end of the standard K of the frame of the machine, by means of the set screw *b*, and upon the said fixed spindle J is loosely pivoted the indicating arm L, which arm is integrally connected with the ratchet guard 95 M. And also upon the said fixed spindle J is loosely pivoted the indicating arm N, which is integrally connected with the ratchet guard O.

The ratchet wheel I is fixedly secured to 105 the hub of the gear wheel P, and at the outer side of the ratchet wheel I is secured the notched stop-wheel Q, the notches *c c* of the said stop-wheel being engaged by the roller R, which is located at the upper end of the 110

bell-crank lever S, the said roller being held in contact with the periphery of the said stop-wheel, by means of the spiral spring d. The gear wheel P is arranged to turn 5 loosely upon the fixed spindle B, being held thereon by means of the adjustable collar e, and upon the said gear wheel and engaging with its teeth are placed a series of multiplying elements consisting of the disks T T T, 10 having one or more notches f in their peripheries, whereby the radial distance of the peripheral surface will be varied and provided with the internal gear teeth g, which engage with the external teeth h of the gear wheel P. The annular multiplying elements 15 T T T are provided with an unequal number of teeth whereby the times of their revolution will be varied, respectively, whereby a comparatively great number of revolutions 20 of the gear wheel P will be required in order that the multiplying elements T T T shall have arrived at such a number of complete revolutions that the peripheral notches f of the several multiplying elements will lie 25 under the laterally elongated bearing head j of the indicating arm L, thus causing the said bearing head to sink into the said notches. And upon the sinking of the head j of the 30 arm L, the ratchet guard M, which is integrally connected with the said arm, will be depressed so as to allow the ratchet pawl F to engage with the teeth of the ratchet wheel H, and thus cause the rotation of the pattern chain sprocket wheel X, which turns loosely 35 upon the fixed spindle B, and to which the said ratchet wheel H is connected. At the side of the ratchet wheel H upon the hub of the pattern chain sprocket wheel X is secured the stop wheel U, the notches k k of 40 which are engaged by the roller R¹ located at the upper end of the bell-crank lever S¹, the said roller being held in contact with the periphery of the said stop-wheel, by means of the spiral spring d¹. Now upon the rotation 45 of the pattern chain sprocket wheel X, such motion will at the proper time cause one of the chain elements V, having a riser, to be brought under the elongated shoe n¹ of the said indicating arm N, thus causing the 50 elevation of the ratchet guard O, and the consequent elevation of the ratchet-pawl G, out of engagement with the teeth of the ratchet wheel I, and thus stopping the action of the multiplying mechanism; and as long 55 as each succeeding element V of the pattern chain is provided with a riser adapted for engagement with the elongated shoe n¹ of the arm N, the multiplying mechanism will remain inoperative, but as soon as a chain element 60 without a riser arrives under the shoe n¹, then the arm N and its integrally connected ratchet guard O will be depressed, thus throwing the multiplying mechanism into operation, and the primary action of the 65 pawl G upon the ratchet wheel I will serve

to cause the rising of the arm L from the peripheral notches f, thus causing the simultaneous elevation of the ratchet guard M, and consequent disengagement of the ratchet pawl F from the teeth of the ratchet wheel H, and the consequent stopping of the action of the sprocket wheel which carries the pattern chain.

A modification of my invention is shown in Fig. 13, in which the multiplying elements 75 are constructed of the endless flexible chains W W, instead of the disks T, one of the chains being made comparatively thin to allow for the depression of the indicating arm L, at the proper time, which time is 80 determined by the occurrence of the depressed chain links o of the several chains W W, in the established line for the action of the indicating arm L. The multiplying elements 85 W W are carried by the sprocket wheels p p, upon the hub of the ratchet wheel I, and the stop wheel Q, and being of unequal dimensions the time of the required coincidence of the indicating elements of the several chains 90 will be greatly extended, and by lengthening or shortening the chains may be regulated as desired.

Another modification of my invention is shown in Figs. 18 and 19, in which the multiplying elements T¹ T² are placed upon the separate spindles B¹ and B² and the indicating arms L¹ L² connected with each other as shown in Fig. 20, the inner end a¹ of the indicating arm L¹ extending under the inner arm b¹ of the said arm L², whereby the movement of the indicating arm L¹ and ratchet guard O¹ cannot be effected until the indicating arm L² has passed into the notch f¹ of the multiplying element T². The ratchet wheels I¹ and I² are operated alternately from 100 the arm E¹ by means of the pawls G¹ and G², and the ratchet guards O¹ O² are operatively connected with each other for simultaneous 105 movement.

Another modification is shown in Figs. 21, 110 22 and 23, in which the peripheries of the multiplying elements T³ T³ are provided with the projections f², instead of the depressions f, or f¹, and in this case the indicating arm L³ is provided with the pivoted 115 catches q q q, which are adapted for normal engagement with the fixed shelf r, but when the said levers are simultaneously engaged by the projections of the several multiplying members, the indicating arm L³ will fall as 120 shown in Fig. 23, and thus insure the desired movement in the connected mechanism.

I claim as my invention:

1. The combination of a plurality of multiplying elements of different internal 125 dimensions, provided at their peripheries with means for causing mechanical movement, driving means for imparting rotary movement to the said elements, indicating means arranged in operative engagement 130

with said elements, and adapted to perform its indicating movement upon the simultaneous arrival of the operating portions of the peripheries of the said indicating elements in the proper position, relatively to each other, for causing the required indicating movement.

2. In an indicating mechanism for looms, the combination of a driving means, a plurality of annular multiplying elements of different diametrical dimensions arranged upon and in positive engagement with the said driving means, and provided at their peripheries with means for causing mechanical movement, an arm arranged for indicating action upon the arrival of the operating portion of the peripheries of the said indicating elements at the proper line for causing the required indicating movement, and a ratchet guard connected with the said indicating arm.

3. In an indicating mechanism for looms, the combination of a driving means, a plurality of annular multiplying elements of different diametrical dimensions arranged upon and in positive engagement with the said driving means, and provided at their peripheries with means for causing mechanical movement, an arm arranged for indicating action upon the arrival of the operating portion of the peripheries of said indicating elements at the proper line for causing the required indicating movement, a ratchet guard connected with the said indicating arm, and the ratchet wheel and pawl of a shuttle box mechanism, whereby upon the occurrence of an indicating movement of the said arm and the connected ratchet guard,

the shuttle box mechanism will be started into operation.

4. In an indicating mechanism for looms, the combination of the pattern chain of a shuttle box mechanism, means for operating the same, an indicating arm operated by the said pattern chain, the ratchet guard connected with the said indicating arm, the ratchet wheel and pawl pertaining to the said ratchet guard, a rotary driving means operated by the action of the said ratchet wheel and pawl, and a plurality of multiplying elements of different diametrical dimensions arranged in positive engagement with the said rotary driving means, whereby the said multiplying elements will be started into varied rotation by the action of the elements of the pattern chain of the shuttle box mechanism.

5. In an indicating mechanism for looms, the combination of a plurality of rotary annular multiplying elements of different diametrical dimensions provided at their peripheries with means for causing mechanical movement, means for imparting a uniform peripheral movement to the said multiplying elements and an arm arranged for indicating action upon the arrival of the operating portions of the peripheries of the said multiplying elements at the proper line for causing the required indicating movement.

WILLARD W. BARDSLEY.
